UNITED STATES PATENT OFFICE.

NELLIE W. LOWE, OF OMAHA, NEBRASKA.

INCINERATING RECEPTACLE AND CHUTE.

949,986.

Specification of Letters Patent. Patented Feb. 22, 1910.

Application filed August 16, 1909. Serial No. 512,990.

To all whom it may concern:

Be it known that I, NELLIE W. LOWE, a citizen of the United States, residing at Omaha, in the county of Douglas and State 5 of Nebraska, have invented certain new and useful Improvements in Incinerating Receptacles and Chutes, of which the following is a specification.

This invention relates to an incinerating 10 receptacle and chute, adapted particularly for use in hospitals.

The object of the invention is to provide, for the use of these institutions, means for the handling and destruction of refuse, such 15 as bandages, gauze, compresses, fabrics exposed to contagion, or other dry or wet refuse which might harbor infection, said means to comprise parts which may be economically constructed and may be readily 20 installed in a building, and which will be convenient in use and sanitary and reliable in operation for effectually destroying the refuse.

The invention also has reference to means 25 for disinfecting the chute and connected parts after they have been used, so that infection may be eliminated.

With these objects in view the invention discloses a novel combination and arrangement 30 of parts as described herein, pointed out by the appended claims, and as illustrated in the accompanying drawing, it being understood that changes in form, size, proportion and minor details may be made 35 within the scope of the claims without departing from the spirit or sacrificing any of the advantages of the invention.

In the drawing, forming a part of the 40 application, Figure 1 is a broken away, side view, in section, of an incinerating receptacle and chute embodying my invention. Fig. 2 is a front view showing the parts illustrated by Fig. 1. Fig. 3 is an enlarged detail, being a side view, partly in section, 45 of the firing disk or pan and fuel pipe. Fig. 4 is a plan view, partly broken away, showing the parts illustrated by Fig. 3, a bifurcated, annular grate being added. Fig. 5 is a vertical, side view, in section, of a modified 50 incinerating receptacle, believed to be within the scope of the invention.

The herein described incinerating receptacle and chute may be constructed to advantage, of galvanized iron or other sheet

metal, but other metallic constructions may 55 be employed, if desired.

Referring to the drawing, the numeral 1 designates an incinerating receptacle comprising a metallic cylindrical casing 2, having a peripheral rib 3 near its bottom. A 60 door opening 4 formed in said receptacle is closed when desired by a hinged door 5. The door 5 is provided with suitable fastenings 6 and with a rib 3' corresponding to rib 3 of the casing 2. A bottom 4' closes 65 the lower end of the casing. Casing 2 is provided with a dome 7 having a smoke pipe 8 communicating with chimney 9. The upper part of the dome is provided with a housing-frame 10 in which may be seated 70 the cut-off or sliding-plate 11, these parts being inclined upwardly and rearwardly in the direction of pipe 8; and pipe 8 is provided with a transverse housing-frame 12 in which is seated sliding-plate 13. I provide 75 the secondary dome 14 disposed above and communicating with dome 7, and having at its upper terminal a horizontal housing-frame 15 in which may be seated the sliding-plate 16.

At 17 is indicated an upright chute, and it may traverse the several floors 33 of a building, its upper terminal communicating with chimney 9, and within convenient 80 manual control, above the upper floor, is provided, transversely in chute 17 a suitable housing-frame 19, in which may be seated sliding-plate 20. In the chute, at a suitable height above each floor, is provided an intake opening 21, stationary spots 22 85 being secured upon the wall of the chute, adjacent these openings, and hinged lids 23 are employed to completely and effectively make closures of the spouts, and dry or saturated fabrics and other similar refuse 90 incident to the care of invalids and usually removed from hospitals to be destroyed, may be conveniently disposed of by passing the same through the intakes mentioned, and as will be seen, the refuse will be destroyed in a 100 convenient and effective manner. Said refuse will fall within receptacle 2, sliding-plates 11 and 16 remaining in withdrawn positions at all times except when the contents of the receptacle are burned, adequate 105 means for the destruction of this refuse to be presently described.

Chute 17 may be located in any desired

part of a building, and of course may pass within an operating room, toilet or nurses room, as may be desired. Intakes 21 and sliding-plate 20 are normally kept closed. 5 Any suitable construction may be employed for the housing-frames mentioned, in which the plates may slide; these frames or sections, however should have an area greater than the pipes or domes wherein they are 10 mounted, and the sliding- plates have an area greater than the openings which they cover, so that a suitable and effective control may be obtained of the passage ways, by use of the sliding-plates. It will be understood 15 that the herein described devices are operative without regard to the number of floors of a building, and the intakes and their connections are so constructed that the use of one does not interfere with the simultaneous use of others. 20

I provide the annular, bifurcated grate 24 having a diameter substantially equal to the interior of casing 2, and adapted to have a seating in the receptacle upon the interior 25 ridge formed by grooves 3 and 3', and since it has a two-part construction, it may be conveniently deposited within the casing when the parts are assembled.

At 25 is indicated a shallow firing pan or 30 disk, adapted to have a seating upon the grate midway of the cylindrical wall of the receptacle. At 26, secured exteriorly of and upon the wall of the receptacle, is indicated an oil cup having a downwardly inclined feed pipe 27 communicating with pipe-section 28, the latter being employed for convenience in assembling the parts, the 35 ends of pipe-section 28 and the terminal of pipe 27, preferably, being threaded to connect with coupling 29, and with stem 30 of pan 25.

Receptacle 1 may be located to advantage 40 in the basement of a building, and when sliding-plates 11 and 16 have been closed, sliding-plate 13 being withdrawn, the 45 devices described will be adequate to destroy damp or wet bandages or similar cast-off material. The firing-pan may be conveniently supplied with oil from the supply- 50 cup, and damp or wet fabrics will become sufficiently saturated with oil to cause incineration thereof.

In practice, the pan is supplied with oil 55 before the refuse is deposited, and it thereby becomes saturated as mentioned. At the time and while the refuse is burning there will be no oil in the supply cup, and danger from fire is eliminated so far as the exterior cup is concerned, and only a sufficient 60 amount of oil is used in the firing-pan to cause a thorough combustion of the refuse. In practice it has been found that galvanized iron is a preferred material for constructing the incinerating receptacle, but in large institutions where the refuse is very consider-

able, there is no objection, and it may be an advantage to use heavier material, for the heat generated in such cases would be more intense, more oil being required.

Sliding-plate 20 remains closed at all 70 times except when it is desired to disinfect the chute. In order that the chute may be kept in a sanitary condition, certain devices are employed now to be explained. To disinfect the chute and parts connected 75 therewith, a time is chosen when no refuse is in receptacle 1. Sliding-plate 20 may be withdrawn for this purpose, sliding-plate 13 and lids 23, of course, being closed, and plates 11 and 16 are withdrawn. A preparation 80 of sulfur mixed with oil or other suitable disinfecting material is placed in firing-pan 25 and is ignited, door opening 4 being available for access thereto. By reason of the draft thus created the fumes of the burning disinfectant will readily fumigate and 85 ventilate the entire chute and its connecting parts.

By the construction shown, it will be noted 90 that domes 7 and 14 and chute 17 have different diameters, the area of a lower compartment through which material passes being greater than an upper compartment, and this is a desired feature, to prevent the deposit upon the walls of these compartments or of lodgment therein of any of the 95 material.

I have shown a portable incinerating receptacle 31, useful particularly in connection with one-story hospital buildings. It 100 consists of the cylindrical casing 2' having a peripheral groove and door and bottom, substantially as already described, together with grate 24' supported upon the annular ridge as described, and upon the grate is 105 supported the firing-pan 25', with a fuel- cup 26' and its connected pipes 27' and 28', the same as mentioned. Refuse may be deposited in receptacle 31, and when deposited out-of-doors, the oil-saturated refuse may be 110 ignited, and the cylindrical wall of the casing will operate to provide a draft, cover 32 being removed at this time.

Having fully described my invention, what I claim and desire to secure by Letters Patent is,—

1. In an incinerating apparatus for destroying germ bearing articles, the combination with a building and its chimney, of a receptacle adapted to retain said articles 120 while they are being consumed, an article carrying chute leading upwardly through the various floors of said building, the upper end of said chute communicating with the chimney, a valved connection between 125 said receptacle and the chimney, means for closing communication between the receptacle and the chute, there being openings formed directly in the side walls of the chute at each floor, and a smoke tight clo- 130

sure at each floor for said openings, said openings permitting the passage of the germ bearing articles into said chute.

2. An incinerating device comprising a receptacle, a firing pan located centrally therein, a foraminous grating extending between the edges of the pan and the wall of the receptacle, and means leading from the exterior of the receptacle to said firing pan

for feeding combustible oil thereinto, said pan and said grating together serving to support articles to be consumed.

In testimony whereof I have affixed my signature in presence of two witnesses.

NELLIE W. LOWE.
